STEAM HEATED RADIATOR

Robert Henri Mautsch, Brussels, Belgium, assignor to The Westinghouse Air Brake Company, Wilmerding, Pa., a corporation of Pennsylvania

Application November 17, 1931, Serial No. 575,512
In Great Britain November 18, 1930

1 Claim. (Cl. 257—159)

This invention relates to steam heating apparatus for railway vehicles and other purposes of the kind in which the radiator of the apparatus is provided with a thermostatically operated regulating mechanism for automatically controlling the supply of steam to the radiator.

The invention has for its object to provide an improved construction of apparatus of this character which shall be relatively light in weight, inexpensive to manufacture and efficient, accurate and reliable in operation.

Another object of the invention is to provide a radiator having two heads connected together by tubular elements and means for venting air from the chamber in one head to an outlet associated with the other head.

The features of the invention involving thermostatic control of the radiator have been included in a division of this application, Serial No. 663,149, filed March 28, 1933.

In order that the invention may be clearly understood a preferred form of construction of radiator embodying the invention will now be described, by way of example with reference to the accompanying drawings, in which:

Figure 1 is a sectional view, on the line I—I of Figure 2 of the improved radiator.

Figure 2 is a sectional view on the line II—II of Figure 1.

Figures 3 and 4 are end views of the radiator looking towards the left and right respectively and Figure 5 is a sectional view on the line V—V of Figure 2.

Referring now to the drawings, the radiator body comprises two hollow end portions or heads 1 and 2 cross-connected by a number of tubular elements 3, 4, and 5 and 6 composed of copper or other suitable metal having a high temperature co-efficient of expansion, the ends of these tubular elements being secured in the heads 1 and 2 in any suitable manner which will provide steam tight joints. The head 2 termed the control head contains the steam inlet valve element 7 adapted to cooperate with a suitable valve seat 8 and control the passage of steam from an inlet pipe connection 9, formed on the head 2, and through a passage 10 and chamber 11, to an internal chamber 12 of the head communicating with the tubular elements 3, 4, 5 and 6.

The valve element 7 is formed integral with or rigidly secured to a regulating rod 13 centrally extending through the tubular element 4 to the other or regulating head 1 of the radiator. The regulating rod 13 is composed of a metal having a relatively low temperature co-efficient of ex-

pansion and at its end within the regulating head 1 carries a flanged guide element 14 which is secured to one end of a cylindrical corrugated element composed of sheet copper or other suitable metal forming a bellows element 15, the other end of which is secured at 16 by a steam tight joint to the interior of the head 1. A spring 17 located within the bellows element tends to move the guide element 14 together with the regulating rod 13 and valve element 7 towards the left, and the guide element 14 is engaged by the inner end of a screw-threaded sleeve 18 mounted in a correspondingly screw-threaded aperture in the head 1 and provided at its outer end with an operating element 19.

The extreme end of the regulating head 1 is provided with an adjustable collar 20 having a lug 21 adapted to co-operate with a lug 22 provided on the operating element 19 and serve as a stop for the latter, the collar 20 being adapted to be secured with the lug 21 in any required position by means of a screw 23.

The chamber 12 in the control head 2 is provided with an outlet 24 for water of condensation, this outlet being, if desired, connected to an outlet or drain pipe, and a tube 25 extending through the tubular element 5 from a chamber 26 in the regulating head to the outlet 24 in the control head serves to conduct air from the chamber 26 to the outlet 24 when steam is supplied to the inlet pipe connection 9. The end of the tube 25 located in the chamber 26 is cut away at each side as indicated in Figure 2.

The operation of the apparatus is as follows:

The operating element 19 can be set into one or other of a number of different positions corresponding for instance to "hot", "moderate" and "cold". In Figures 1 and 2 it is shown in its extreme position (hot), this position being defined by the lug or stop 21 on the collar 20, which can be moved into any required position with respect to the regulating head 1 and retained therein by means of the screw 23 so as correspondingly to define the extreme position of the operating element 19.

When the operating element 19 is rotated anti-clockwise (Figure 4) to the "cold" position the outward movement of the screw-threaded sleeve 18 permits a corresponding movement of the regulating rod 13 under the action of the spring 17 thereby allowing the valve element 7 to move to its closed position on its seat 8.

With the operating element set in an intermediate or "moderate" position the regulating rod 13 is moved towards the right (Figures 1 and

2) with the result that the valve element 7 is moved away from its seat 8 and permits the inlet of steam into the internal chamber 12 of the control head and thence into the tubular elements 3, 4, 5 and 6. The latter will thereby be heated and owing to their expansion tend to move the regulating head 1, which is arranged to be free to move, away from the control head 2, which is fixed, this expansion causing the 10 valve element 7 to re-engage the seat 8 and thereby prevent the further admission of steam as soon as the radiator has attained a corresponding temperature.

A similar action occurs when the operating 15 element 19 is adjusted to its "hot" position (Figures 1 and 2), the admission of steam past the valve element 7 to the tubular elements 3, 4, 5 and 6 being, however continued until the radiator has attained a correspondingly higher tem-

20

perature so that the tubular elements have expanded to a greater extent. The tubular elements 3, 4, 5 and 6 are as shown in the drawings provided with radiating fins 27 and it will be understood that owing to the rapidity with which the tubular elements are heated the regulating action is extremely prompt and efficient.

Having now described my invention, what I claim as new and desire to secure by Letters Patent, is:—

Steam heating apparatus for railway vehicles comprising a radiator having two heads connected together by tubular elements, each head having a chamber, and a tubular member extending through one of the tubes of the radiator and having one end open to one of said chambers and the other end connected to an outlet at the other chamber.

ROBERT HENRI MAUTSCH.
